UNITED STATES PATENT OFFICE.

CHAUNCEY MARSH GOODRICH, OF WINDSOR, ONTARIO, CANADA.

TURNTABLE CENTER.

Application filed December 23, 1926, Serial No. 156,686, and in Canada December 14, 1926.

This invention has relation to certain new and useful improvements in turntable centers and more particularly the center bearing structure thereof.

5 The invention has for an object the provision of a turntable center structure including center bearing members of improved construction and on which the main transverse girders of the turntable are mounted and 10 connected with the upper bearing casting or member through the medium of a pair of vertically removable pins having tapered lower extremities received in pockets provided therefor in the upper bearing casting, 15 after the pins are extended through the horizontally removable bearing plate.

Another object of the invention resides in the provision of a turntable center in which the parts may be readily assembled and connected by the vertically removable pins dropped down through the frame casting between the main horizontal center beams of the turntable, or the portions of the center bearing removed and inspected or replaced 25 by simply withdrawing or raising up vertically the vertical locking and centering pins.

A further object of the invention resides in the provision of a turntable center of the character stated in which bearing disks and 30 a bearing sleeve are employed between the lower and upper center bearing castings or members and means provided for thoroughly lubricating the bearing members and the portions of the castings working thereon to assure efficient operation and reduce friction 35 to the minimum, during operation of the turntable.

The invention has for a still further object, the provision of a center bearing of the 40 character stated composed of the minimum number of parts of simple construction and which may be readily assembled or taken apart after inserting or removing, vertically the vertical bearing pins which are moved 45 vertically between the main horizontal center beams of the turntable and without the necessity of first raising or jacking up the turntable proper.

With the foregoing and other objects in 50 view, as will appear as the description proceeds, the invention consists of the novel construction, combination and arrangement of

cooperating elements, as hereinafter more specifically set forth, claimed and shown in the accompanying drawings forming a part 55 of the present application and in which—

Figure 1 is an elevation of the improved center bearing structure, partially in section.

Figure 2 is a vertical section, substantially on the plane of line II—II of Figure 1, 60 looking in the direction indicated by the arrows, partially in elevation.

Figure 3 is a vertical section, substantially on the plane of line III—III of Figure 2, 65 looking in the direction indicated by the arrows.

Figure 4 is a top plan of the upper bearing or member.

Figure 5 is a detail perspective of the horizontally removable bearing plate.

Referring more in detail to the drawings in which similar characters designate corresponding parts throughout the several views, it is to be noted that the center bearing structure includes a lower casting or base member 11, which is firmly anchored on a concrete base or the like 12 by anchoring bolts 13, as shown clearly in Figures 1 to 3 inclusive. The bottom casting or base member 11 has a central concentric upstanding portion 14 with a horizontal upper plate 15 on its upper edge, thus forming a hollow central chamber 16. A central upstanding sleeve 17, is carried on the plate 15 and also an outer concentric upstanding flange 18 on the outer portion of the plate 15, outwardly of the portion 14 of the casting and near the edge of the plate 15, as shown clearly in Figures 2 and 3. A plurality of spaced triangular ribs 19 are also provided as a part 80 of the bottom casting, the lower edges of the ribs 19 connecting with the bottom plate 11 of the casting while their inner and upper edges connect with the upstanding portion 14, the upper plate 15 and the upstanding outer flange 18. The outer free edges of the ribs 19 are inclined and it will be evident 85 that the ribs 19 serve to reinforce and strengthen the entire base member or casting. It will also be seen clearly from Figures 1 and 2 that the anchoring bolts 13 are located between the radially extended ribs 19.

The upper bearing member or casting 20 is inverted and is provided with a depending

and concentric central sleeve or flange 21 adapted to surround the upstanding sleeve or flange 17 of the bottom casting or base member 11 when the upper bearing member 20 or casting 20 is in position, as shown in the drawings. The sleeve or flange 21, however, is spaced from and surrounds the upper portion only of the sleeve or flange 17 so as to receive and accommodate the vertical bearing sleeve 22 between the sleeves 17 and 21. An intermediate depending annular sleeve or flange 23 is also provided on the upper bearing member or casting 20, outwardly of the sleeve or flange 21. A pair of bearing disks 24 are interposed on the upper face of the raised main part 15^a of the upper plate 15 of the bottom casting or base member 11. The bearing rings 24 surround the lower part of the bearing sleeve 22 and the lower and upper bearing rings 24 have, respectively, threaded therein pairs of depending pins 25 engaged in pockets 26 of the plate 15 and upstanding pins 27 engaged in pockets 28 provided therefor in the bottom 25 of the sleeve or flange 23, thus locking the lower and upper bearing rings 24 with the base member or bottom casting 11 and the upper casting or bearing member 20, respectively, to assure rotation of the upper bearing ring 24 on the lower bearing ring 24 as the upper casting or bearing member 20 is rotated on the base member or bottom casting 11, during operation of the turntable, as will be later clearly apparent. It will be 30 clearly seen from Figures 2 and 3 that the weight of the upper bearing member or casting 20 and the entire turntable structure resting thereon is transmitted to the bearing rings 24 through the spaced concentric sleeves or flanges 21 and 23 of the upper casting or bearing member 20 resting on the upper face of the upper bearing ring 24 and an inner oil or lubricant receiving reservoir 29 is formed above the bearing rings 24 and 35 in the upper casting or bearing member 20, by the depending sleeves or flanges 21 and 23. Oil or lubricant passage grooves 30 are formed in the lower edge of the sleeve or flange 23 to permit passage of the oil or other lubricant from the oil or lubricant reservoir 29 to the outer oil or lubricant reservoir 31, surrounding the sleeve or flange 23 and the bearing ring 24 and having its outer wall formed by the upstanding outer flange 18 of the bottom casting 11, and the outwardly flared depending outer flange 32 of the upper bearing casting 20. It will be 40 readily seen by referring to Figures 2 and 3, that the flange 32 has its lower edge 33 directed downwardly and engaged around the reduced upper edge portion 34 of the flange 18 to assure proper fitting of the casting of upper bearing member and rotation thereof on the bottom casting or base member 11. A plurality of pairs of radially di-

rected ribs 35 are provided on the outer face of the casting or upper bearing member 20. Openings 36 are provided in the ribs 35 to receive suitable tools for holding the casting or upper bearing members when placing the same in position or raising the casting or upper bearing member from upon the lower casting or base member 11. It will also be understood that similar openings 37 are provided in the ribs 19 so that the lower casting or base member 11 may be properly handled when being placed in position on the concrete base 12 or removed therefrom. A lubricant supply pipe 38 has a turned lower end 39 with a threaded extension 40 secured in the upper portion of the bearing member or casting 20 and opening into the upper portion of the inner lubricant reservoir 29, as shown clearly in Figure 2. The upstanding portion of the lubricant supply pipe 38 may have an appropriate lubricant accommodating cup 41 provided thereon, as also shown in Figure 2. The upper bearing member or casting 20 has an elongated flat upper central portion 42 which is provided with a pair of tapered spaced pockets 43 equal distances from the center of the casting 20 to receive the tapered lower ends 44 of vertical centering and locking pins 45 employed for centering and locking the turntable proper on the center bearing structure. The pins 45 are extended through and supported in the frame casting 46 which is adapted to rest on the horizontally removable center bearing plate 47 which in turn is adapted to rest on the portion 42 of the casting or upper bearing member 20. The plate 47 is provided with spaced pin accommodating openings 48 adapted to register with the pockets 43 and the pin openings 49 provided in the frame casting 46, when such parts are in alinement with one another on the center bearing structure as shown in the drawings. The frame casting 46 is suspended between the spaced cross beams 50 which are securely fastened to the reduced upper portions 51 of the frame casting 46 and on opposite sides thereof, as shown clearly in Figure 2, by rivets 52 or other suitable means. The cross beams 50 extend above the frame casting 46 and spacing plates 52 are secured on their outer faces, along their upper edges. The fastening members employed for this purpose, also extend through the main portions of the angle plates 54 and 55 and the vertical spacing plates positioned therebetween and also through the outer plates 57 on either side of the frame casting 46. The angle plates 54 and 55 have their upper portions 58 and 59, respectively, turned in opposite directions and secured at their ends to the under face of the upper flanges 60 of the spaced pair of main transverse beams 61 of the turntable structure proper. Rivets 62 or other

appropriate means may be employed for securing together the lower edge portions of the angle irons 54, the plates 56 and 57 and the upturned angle portions of the angle bars 63 inserted between the lower parts of the plates 56 and 57. The outturned angular portions 64 of the angle bars 63 are secured at opposite ends to the lower flange 65 of the main transverse center beams 61 of the turntable proper structure. It will, therefore, be seen that the frame casting 46 extends transversely of the main transverse center beams 61 of the turntable proper structure and thus supports the pair of vertically insertable and removable locking pins 45 employed for locking the turntable proper structure on its center bearing. The pins 45 may be readily inserted or removed by suitable tools or instruments engaged through openings 66 provided for this purpose in the upper extended portions of the pins 45, as shown in Figures 1 and 2.

It is believed the complete construction and operation may be now apparent from the foregoing paragraphs taken in connection with the accompanying drawings without further detail description. The mounting of the various parts and their cooperation and also the manner of disconnecting the turntable proper structure from the center bearing structure for inspection or repair of the latter may be briefly stated, however, as follows:

The upper casting or bearing member 20 may readily be raised and passed over the flange 31 of the lower casting or base member 11 when being placed in position on or removed from the latter. It is also clear that the pins 45 must be raised and the horizontally removable bearing plate 47 removed horizontally previous to raising of the upper casting or bearing member 20 above the bottom casting or base member 11, if the main center beams of the turntable proper structure are in position as shown in the drawings with the frame casting 46 above the center bearing structure to accommodate the vertically removable locking pins 45. The bearing disks 24 and the bearing sleeve 22 may be readily placed in position or removed when the upper casting or member is removed vertically from its position on the lower bearing or base member 11 by suitable means engaged with the perforated ribs 35. It is also evident that the bottom casting or base member 11 may be raised and lowered vertically by appropriate means engaged with the perforated ribs 19 thereof.

Before removing the bearing plate 47, the turntable will preferably be blocked up to prevent sagging when the plate 47 is removed, and in some instances, it may be necessary to raise the table by the use of wedges or jacks sufficiently to remove the

weight of the table from the bearing plate 47 in order to facilitate the removal and replacement of such plate.

As all of the parts of the center bearing structure as well as the locking pins 45 for locking the turntable proper structure on the center bearing structure, may be readily raised or lowered vertically (the bearing plate 47 being removable and insertable horizontally when the locking pins 45 are lifted sufficiently to clear the same and this bearing plate 47 being the only part which is not separated from the other parts or placed in position in respect thereto by movement through a vertical plane) all of the parts may be readily assembled or disconnected without the necessity of first jacking up the turntable proper structure any appreciable amount. Furthermore, the only connection between the turntable proper structure and the center bearing structure in this invention, is made by the vertical locking pins 45 which are insertable and removable vertically between the main center beams 61 of the turntable proper structure.

While the preferred embodiment of the invention has been disclosed, it is to be understood that minor changes in the detailed construction, combination and arrangement of cooperating elements, may be resorted to within the scope of the appended claims without departing from the spirit of the invention.

I claim—

1. In a turntable center structure, including the combination with a turntable proper and a rotatable center bearing member adapted to be vertically removed from its operable position without first lifting or jacking up the turntable proper, of vertically removable or insertable centering and locking pins extending through the turntable proper and into said center bearing member.

2. In a turntable center structure, the combination with a turntable proper including main center beams with a frame bearing therebetween and a rotatable center bearing member adapted to be removed and placed in position vertically without first raising or jacking up the turntable proper, of a pair of vertically removable centering and locking members working through said frame bearing on opposite sides of the center of said bearing member, said centering and locking members having tapered lower ends receivable in pockets provided therefor in said center bearing member.

3. In a turntable center structure, the combination with a center bearing member and a supporting frame bearing carried by the turntable proper, of vertically removable and insertable centering and locking means supported in said supporting frame bearing and engageable with said center bearing

member, and an intermediate bearing plate insertable and removable horizontally between said turntable proper and said center bearing member, said bearing plate being provided with openings to accommodate said centering and locking means when the latter are in operative position.

4. In a turntable structure, the combination with a center bearing and a turntable proper, of vertically removable and insertable centering and locking means carried by the turntable proper and engageable with said center bearing, and an intermediate bearing plate insertable and removable horizontally between said turntable proper and said center bearing member, said bearing plate being provided with openings to accommodate said centering and locking means when the latter are in operative position.

5. In a turntable center structure, the combination with a rotatable center bearing and the turntable proper, of a pair of vertically removable and insertable centering and locking members operable through the turntable proper and engageable in said rotatable bearing member, and an intermediate bearing plate insertable and removable horizontally between said turntable proper and said center bearing member, said bearing plate being provided with openings to accommodate said centering and locking members when the latter are in operative position.

6. In a turntable center structure, including the combination with a turntable proper and a rotatable center bearing member adapted to be vertically removed from its operable position without first lifting or jacking up the turntable proper, of vertically removable or insertable centering and locking pins extending through the turntable proper and into said center bearing member, and an intermediate bearing plate insertable and removable horizontally between said turntable proper and said center bearing member, said bearing plate being provided with openings to accommodate said centering and locking pins when the latter are in operative position.

7. In a turntable center structure, the combination with a turntable proper including main center beams with a frame bearing therebetween and a rotatable center bearing member adapted to be removed and placed in position vertically without first raising or jacking up the turntable proper, of a pair of vertically removable centering and locking members working through said frame bearing on opposite sides of the center of said bearing member, said centering and locking members having tapered lower ends receivable in pockets provided therefore in said center bearing member, and an intermediate bearing plate insertable and removable horizontally between said turntable

proper and said center bearing member, said bearing plate being provided with openings to accommodate said centering and locking members when the latter are in operative position.

8. In a turntable center structure, the combination with a center bearing member and a supporting frame bearing carried by the turntable proper, of vertically removable and insertable centering and locking means supported in said supporting frame bearing and engageable with said center bearing member, a stationary base center bearing member having an upstanding flange and a center sleeve, a bearing sleeve surrounding said center sleeve, superimposed bearing rings mounted on said base bearing member around said bearing sleeve, the first mentioned center bearing member having spaced annular depending flanges resting on said bearing rings and surrounding the upper portion of said bearing sleeve, said first mentioned center bearing member having an outer annular flange overlapping and riding on the annular flange of said base center bearing member, thus providing inner and outer lubricant reservoirs above and surrounding, respectively, said bearing rings, said first mentioned or upper center bearing member having grooves to form communication between said inner and outer lubricant reservoirs, said base center bearing member and said upper center bearing member having perforated radial ribs to receive lifting tools, and means for locking the lower and upper bearing rings with said base center bearing member and said upper center bearing member respectively.

9. In a turntable structure, the combination with a center bearing and a turntable proper, of vertically removable and insertable centering and locking means carried by the turntable proper and engageable with said center bearing, a stationary base center bearing member having an upstanding flange and a center sleeve, a bearing sleeve surrounding said center sleeve, superimposed bearing rings mounted on said base bearing member around said bearing sleeve, the first mentioned center bearing member having spaced annular depending flanges resting on said bearing rings and surrounding the upper portion of said bearing sleeve, said first mentioned center bearing member having an outer annular flange overlapping and riding on the annular flange of said base center bearing member, thus providing inner and outer lubricant reservoirs above and surrounding, respectively, said bearing rings, said first mentioned or upper centering bearing member having grooves to form communication between said inner and outer lubricant reservoirs, said base center bearing member and said upper center bearing member having perforated radial ribs to re-

5

ceive lifting tools, and means for locking the lower and upper bearing rings with said base center bearing member and said upper center bearing member, respectively.

- 5 10. In a turntable center structure, the combination with a rotatable center bearing and the turntable proper, of a pair of vertically removable and insertable centering and bearing members operable through the turntable proper and engageable in said rotatable bearing member, a stationary base center bearing member having an upstanding flange and a center sleeve, a bearing sleeve surrounding said center sleeve, superimposed bearing rings mounted on said base bearing member around said bearing rings and surrounding the upper portion of said bearing sleeve, said first mentioned center bearing member having an outer annular flange overlapping and riding on the annular flange of said base center bearing member, thus providing inner and outer lubricant reservoirs above and surrounding, respectively, said bearing rings, said first mentioned or upper center bearing member having grooves to form communication between said inner and outer lubricant reservoirs, said base center bearing member and said upper center bearing member having perforated radial ribs to receive lifting tools, and means for locking the lower and upper bearing rings with said base center bearing member and said upper center bearing member, respectively.

35 11. In a turntable center structure, including the combination with a turntable proper and a rotatable center bearing member adapted to be vertically removed from its operable position without first lifting or jacking up the turntable proper of vertically removable or insertable centering and locking pins extending through the turntable proper and into said center bearing member, a stationary base center bearing member having an upstanding flange and a center sleeve, a bearing sleeve surrounding said center sleeve, superimposed bearing rings mounted on said base bearing member around said bearing sleeve, the first mentioned center bearing member having spaced annular depending flanges resting on said bearing rings and surrounding the upper portion of said bearing sleeve, said first mentioned center bearing member having an outer annular flange overlapping and riding on the annular flange of said base center bearing member, thus providing inner and outer lubricant reservoirs above and surrounding, respectively, said bearing rings, said first mentioned or upper center bearing member having grooves to form communication between said inner and outer lubricant reservoirs, said base center bearing member and said upper center bearing member having perforated radial ribs to receive lifting

tools, and means for locking the lower and upper bearing rings with said base center bearing member and said upper center bearing member, respectively.

12. In a turntable center structure, the combination with a turntable proper including main center beams with a frame bearing therebetween and a rotatable center bearing member adapted to be removed and placed in position vertically without first raising or jacking up the turntable proper, of a pair of vertically removable centering and bearing members working through said frame bearing on opposite sides of the center of said bearing member, said centering and locking members having tapered lower ends receivable in pockets provided therefor in said center bearing member. 70 75 80

13. In a turntable center structure, the combination with a center bearing member and a supporting frame bearing carried by the turntable proper, of vertically removable and insertable centering and locking means supported in said supporting frame bearing and engageable with said center bearing member, and an intermediate bearing plate insertable and removable horizontally between said turntable proper and said center bearing member, said bearing plate being provided with openings to accommodate said centering locking means when the latter are in operative position, a stationary base center bearing member having an upstanding flange and a center sleeve, a bearing sleeve surrounding said center sleeve, superimposed bearing rings mounted on said base bearing member around said bearing sleeve, the first mentioned center bearing member having spaced annular depending flanges resting on said bearing rings and surrounding the upper portion of said bearing sleeve, said first mentioned center bearing member having an outer annular flange overlapping and riding on the annular flange of said base center bearing member, thus providing inner and outer lubricant reservoirs above and surrounding, respectively, said bearing rings, said first mentioned or upper centering bearing member having grooves to form communication between said inner and outer lubricant reservoirs, said base center bearing member and said upper center bearing member having perforated radial ribs to receive lifting tools, and means for locking the lower and upper bearing rings with said base center bearing member and said upper center bearing member respectively.

14. In a turntable structure, the combination with a center bearing and a turntable proper, of vertically removable and insertable centering and locking means carried by the turntable proper and engageable with said center bearing, and an intermediate bearing plate insertable and removable horizontally between said turntable proper and

said center bearing member, said bearing plate being provided with openings to accommodate said centering and locking means when the latter are in operative position, a 5 stationary base center bearing member having an upstanding flange and a center sleeve, a bearing sleeve surrounding said center sleeve, superimposed bearing rings mounted on said base bearing member around said bearing sleeve, the first mentioned center bearing member having spaced annular depending flanges resting on said bearing rings and surrounding the upper portion of said bearing sleeve, said first mentioned center bearing member having an outer annular flange overlapping and riding on the annular flange of said base center bearing member, thus providing inner and outer lubricant reservoirs above and surrounding, 10 respectively, said bearing rings, said first mentioned or upper center bearing member having grooves to form communication between said inner and outer lubricant reservoirs, said base center bearing member and 15 said upper center bearing member having perforated radial ribs to receive lifting tools, and means for locking the lower and upper bearing rings with said base center bearing member and said upper center bearing member respectively.

15. In a turntable center structure, the combination with a rotatable center bearing and the turntable proper; of a pair of vertically removable and insertable centering and bearing members operable through the turntable proper and engageable in said rotatable bearing member, and an intermediate bearing plate insertable and removable horizontally between said turntable proper and 20 said center bearing member, said bearing plate being provided with openings to accommodate said centering and locking means when the latter are in operative position, a stationary base center bearing member having an upstanding flange and a center sleeve, a bearing sleeve surrounding said center sleeve, superimposed bearing rings mounted on said base bearing member around said bearing sleeve, the first mentioned center bearing member having spaced annular depending flanges resting on said bearing rings and surrounding the upper portion of said bearing sleeve, said first mentioned center bearing member having an outer annular flange overlapping and riding on the annular flange of said base center bearing member, thus providing inner and outer lubricant reservoirs above and surrounding, 25 respectively, said bearing rings, said first mentioned or upper center bearing member having grooves to form communication between said inner and outer lubricant reservoirs, said base center bearing member and said upper center bearing member having perforated radial ribs to receive lifting tools, and means for locking the lower and upper bearing rings with said base center bearing member and said upper center bearing member respectively.

16. In a turntable center structure, including the combination with a turntable proper and a rotatable center bearing member adapted to be vertically removed from its operable position without first lifting or jacking up the turntable proper, of vertically removable or insertable centering and locking pins extending through the turntable proper and into said center bearing member, and an intermediate bearing plate insertable and removable horizontally between said turntable 70 proper and said center bearing member, said bearing plate being provided with openings to accommodate said centering and locking pins when the latter are in operative position, a stationary base center bearing member having an upstanding flange and a center sleeve, a bearing sleeve surrounding said center sleeve, superimposed bearing rings mounted on said base bearing member around said bearing sleeve, the first mentioned center bearing member having spaced annular depending flanges resting on said bearing rings and surrounding the upper portion of said bearing sleeve, said first mentioned center bearing member having an outer annular flange overlapping and riding on the annular flange of said base center bearing member, thus providing inner and outer lubricant reservoirs above and surrounding, 75 respectively, said bearing rings, said first mentioned or upper center bearing member having grooves to form communication between said inner and outer lubricant reservoirs, said base center bearing member and said upper center bearing member having perforated radial ribs to receive lifting tools, and means for locking the lower and upper bearing rings with said base center bearing member and said upper center bearing member respectively.

17. In a turntable center structure, the combination with a turntable proper including main center beams with a frame bearing therebetween and a rotatable center bearing member adapted to be removed and placed in position vertically without first raising or jacking up the turntable proper, of a pair of vertically removable centering and locking members working through said frame bearing on opposite sides of the center of said bearing member, said centering and locking members having tapered lower ends receivable in pockets provided therefor in said center bearing member, and an intermediate bearing plate insertable and removable horizontally between said turntable proper and said center bearing member, said bearing plate being provided with openings to accommodate said centering and locking members when the latter are in operative 80 position, a stationary base center bearing member having an upstanding flange and a center sleeve, a bearing sleeve surrounding said center sleeve, superimposed bearing rings mounted on said base bearing member around said bearing sleeve, the first mentioned center bearing member having spaced annular depending flanges resting on said bearing rings and surrounding the upper portion of said bearing sleeve, said first mentioned center bearing member having an outer annular flange overlapping and riding on the annular flange of said base center bearing member, thus providing inner and outer lubricant reservoirs above and surrounding, 85 respectively, said bearing rings, said first mentioned or upper center bearing member having grooves to form communication between said inner and outer lubricant reservoirs, said base center bearing member and said upper center bearing member having perforated radial ribs to receive lifting tools, and means for locking the lower and upper bearing rings with said base center bearing member and said upper center bearing member respectively.

18. In a turntable center structure, the combination with a turntable proper including main center beams with a frame bearing therebetween and a rotatable center bearing member adapted to be removed and placed in position vertically without first raising or jacking up the turntable proper, of a pair of vertically removable centering and locking members working through said frame bearing on opposite sides of the center of said bearing member, said centering and locking members having tapered lower ends receivable in pockets provided therefor in said center bearing member, and an intermediate bearing plate insertable and removable horizontally between said turntable proper and said center bearing member, said bearing plate being provided with openings to accommodate said centering and locking members when the latter are in operative 90 position, a stationary base center bearing member having an upstanding flange and a center sleeve, a bearing sleeve surrounding said center sleeve, superimposed bearing rings mounted on said base bearing member around said bearing sleeve, the first mentioned center bearing member having spaced annular depending flanges resting on said bearing rings and surrounding the upper portion of said bearing sleeve, said first mentioned center bearing member having an outer annular flange overlapping and riding on the annular flange of said base center bearing member, thus providing inner and outer lubricant reservoirs above and surrounding, 95 respectively, said bearing rings, said first mentioned or upper center bearing member having grooves to form communication between said inner and outer lubricant reservoirs, said base center bearing member and said upper center bearing member having perforated radial ribs to receive lifting tools, and means for locking the lower and upper bearing rings with said base center bearing member and said upper center bearing member respectively.

position, a stationary base center bearing member having an upstanding flange and a center sleeve, a bearing sleeve surrounding said center sleeve, superimposed bearing rings mounted on said base bearing member around said bearing sleeve, the first mentioned center bearing member having spaced annular depending flanges resting on said bearing rings and surrounding the upper portion of said bearing sleeve, said first mentioned center bearing member having an outer annular flange overlapping and riding on the annular flange of said base center bearing member, thus providing inner and outer lubricant reservoirs above and surrounding, respectively, said bearing rings, said first mentioned or upper center bearing member having grooves to form communication between said inner and outer lubricant reservoirs, said base center bearing member and said upper center bearing member having perforated radial ribs to receive lifting tools, means for locking the lower and upper bearing rings with said base center bearing member and said upper center bearing member, respectively, said upper center bearing member having tapered pockets on opposite sides of the center thereof in its upper portion to receive vertically insertable and removable locking pins extended through a turntable proper for centering and locking the turntable proper on the center bearing structure, and a horizontally removable and replaceable bearing plate adapted to rest on said upper center bearing member and provided with openings adapted to register with the pockets in said upper center bearing member and accommodate said centering and locking pins when the latter are in operative position.

18. In a turntable center structure, the combination of an upper center bearing member, a stationary base center bearing member having an upstanding flange and a center sleeve, a bearing sleeve surrounding said center sleeve, superimposed bearing rings mounted on said base bearing member around said bearing sleeve, the first mentioned center bearing member having spaced annular depending flanges resting on said

In testimony whereof, I have hereunto signed my name.

CHAUNCEY MARSH GOODRICH.
